UNITED STATES PATENT OFFICE.

HERMANN NEHLSEN, OF NIEDERSCHÖNHAUSEN, GERMANY, ASSIGNOR TO GENERAL ELECTRIC COMPANY, A CORPORATION OF NEW YORK.

VOLTAGE-REGULATING MEANS.

1,084,469.

Specification of Letters Patent. Patented Jan. 13, 1914.

Application filed August 30, 1912. Serial No. 717,919.

To all whom it may concern:

Be it known that I, HERMANN NEHLSEN, a subject of the Emperor of Germany, residing at Niederschönhausen, Germany, have invented certain new and useful Improvements in Voltage-Regulating Means, of which the following is a specification.

My invention relates to voltage regulating means employing an induction regulator and a regulating transformer provided with taps, and the principal objects of my invention are to allow a simplification of the switching mechanism and often a reduction in the size of the regulator.

It is common to regulate an alternating current voltage by means of a regulating transformer by changing a terminal connection to different taps regularly spaced therein, using an induction potential regulator in parallel to the individual steps of the transformer to give a smooth, gradual change as the terminal is carried from one tap to another. The maximum voltage of the induction regulator is at least substantially equal to the voltage between two taps. Heretofore the line terminal which is carried from one tap to another has been connected to one (electrical) end of the secondary winding of the induction regulator, the other end of that winding being connected to different taps in succession; in other words the connections were such that the operating current traversed the entire length of the secondary winding of the induction regulator. In accordance with my invention I connect the movable line terminal to substantially the center point, electrically, of the secondary winding of the induction regulator; the two ends thereof, then, are alternately connected to taps. But half the length of the secondary winding of the regulator is at any one time traversed by the entire operating current and for some periods of time the entire secondary winding is traversed by but one-half of the working current. By my invention therefore the induction regulator needs to be of only one-half the rated capacity of the regulator heretofore employed; the switching mechanism employed for making and breaking the required connections in the proper order, it has been found, may be much simplified.

In addition to the switching means for making and breaking the connections be-

tween the ends of the regulator secondary and the taps, I provide switching means for short circuiting the secondary winding of the potential regulator portion of the apparatus, thus connecting the movable terminal direct to a tap, and avoiding the losses in the regulator. In numerous cases also, the whole arrangement allows the use of a smaller regulator as is explained later.

The figures of the accompanying drawing illustrate my invention. It will be understood that these illustrations are entirely diagrammatic and that the relative location of the parts and the independent control of the regulator and the different switches is not essential.

No attempt has been made to show a commercial form of switching mechanism; a highly developed form will probably be used with the regulating apparatus in practice.

Figure 1 illustrates my invention embodied in an induction regulator and a regulating transformer, the regulator being in the position where it is neither adding to nor subtracting from the electromotive force of the working part of the transformer and is short-circuited; Fig. 2 illustrates the same devices, the regulator being so positioned that the movable line terminal is, electrically, half way between two taps; and Fig. 3 shows my invention applied to a polyphase voltage regulating means.

The transformer winding *t* is one of the windings of a regulating transformer *T*, to one end of which is connected a main or line terminal *m*. The movable main or line terminal *n* I connect to substantially the electrical center of the induction regulator secondary winding *s*. The ends *a* and *b* of the secondary winding *s* of the potential regulator are to be connected in succession with the taps 1, 2, 3 and 4 of the winding *t*, as the movable line terminal *n* is carried along and the voltage varied. The primary winding of the induction regulator *e* may be connected to any suitable source of current, as, for example, across the winding *t* as shown. The usual short-circuited secondary *h* may be employed.

In the position of the regulator shown in Fig. 1, the regulator secondary *s* is electrically at right angles to its primary *e*, and hence no voltage is induced therein. Supposing for the moment that the short-circuited

cuiting switch 5 is open, the short-circuited secondary s lowers the reactance of the secondary s to a negligible value and hence the voltage impressed on the terminals 5 m and n is the voltage between the terminal m and the tap 1. The connection from the terminal n to the tap 1 it will be seen is through one-half of the secondary s , the lead a and the switch 1_a ; only one-half of 10 the secondary therefore carries the entire load current. Since the regulator is doing no work, it may be short-circuited by means of the short-circuiting switch 5, as has been shown accomplished in Fig. 1. The secondary s is now in parallel to the switch 5, and as a result carries practically no current and is the source of no loss of energy. Should it now be desired to change the voltage between the terminals m and n ; the 15 switch 5 is first opened. The secondary s is then turned about its axis and the voltage induced therein rises gradually from zero to its maximum, should its rotation be continued thus far; the maximum voltage is 20 reached in the position illustrated in Fig. 2 when the secondary s is electrically parallel with the primary e . The maximum voltage of the secondary s is by predesign substantially equal to the voltage between each pair 25 of taps, and the secondary s is so wound and connected that its voltage is at every instant in the same direction as the voltage in the winding t , as has been indicated by the arrows in Fig. 2 which may represent the 30 direction of the voltages at some instant. With the secondary in this position, the voltage between the terminals m and n is equal to the voltage induced between the terminal m and a point electrically midway between 35 the taps 1 and 2; the half of the secondary winding between its connection to the terminal n and the terminal a is still carrying the full load current. Since, however, the 40 voltage of the secondary s is equal and opposed to the voltage between the terminals 1 and 2, the switch 2_b may be closed, the only effect being to distribute the load current between the two halves of the secondary s . Should it be desired to continue the variation 45 of the voltage between the terminals m and n to that between the terminal m and the tap 2, the rotation of the secondary s may be continued in the same direction until it becomes electrically perpendicular to 50 the primary e . Prior to its continued rotation from the position shown in Fig. 2, the switch 1_a has been open to prevent an interchange of current between the taps 1 and 2 due to their constant difference of potential 55 and the decreasing voltage induced in the winding s . When the secondary again reaches a position electrically perpendicular to its primary e , the short-circuiting switch 6 may be closed and all the apparatus is then in the same relation as illus- 60

trated in Fig. 1, with the exception that the terminal n is now connected direct to the tap 2 rather than to the tap 1. A cycle of operations has been completed and this cycle may be repeated in either direction as desired or required. 70

The short-circuiting switches 5 and 6 are particularly useful where it is necessary for the terminal n to remain for more or less long periods of time in direct connection with certain of the taps. If the transition periods are short, that is the periods during which the terminal n is in movement between two taps, and the periods of direct connections of the terminal n to the taps are relatively long, a smaller regulator than would otherwise suffice, may be used, since such a regulator will stand the overloading required for the short transition periods, it being for the greater periods of operation short circuited by the short-circuiting switches. While the reduction in size may not be so appreciable where the regulator is required to remain in the position shown in Fig. 2 for more or less long periods the size of the regulator may be considerably reduced providing the transition periods to and from this position are short. The connection of the terminal n to the electrical center point of the secondary s , also allows a considerable simplification of the switching device, which ordinarily comprises a single structure, the various switching contacts operating in their proper order and at the proper times relative to the position of the regulator secondary s . 90

For three-phase transformers, the potential regulator is also to be built three-phase. Each short-circuit of the regulator in the positions equivalent to that shown in Fig. 1, must then contain resistance. This effect is preferably obtained by using a double regulator, as shown in Fig. 3. The halves of the secondary winding of the two portions are connected so that their electro-motive forces are opposite in direction before the short-circuiting of the corresponding phases. This double potential regulator will at the same time serve, in the well known manner, to compensate for the phase displacement produced by a single regulator. 100

In Fig. 3 the reference characters are similar to those of the preceding figures, but the characters are furnished in addition with numbers indicating the phases to which the parts are related. 110

t_1 , t_2 , t_3 are windings of a three-phase regulating transformer provided with taps. The primary windings e'_1 , e'_2 , e'_3 and e''_1 , e''_2 , e''_3 of the two parts of the double regulator are here shown, by way of example, connected star and connected in parallel to the phases cf_1 , cf_2 , cf_3 of the transformer. If the two primary wind- 125 130

ings of the double regulator are arranged on the two stationary members thereof in opposite directions, as shown, so that the rotating fields created by them rotate in 5 opposite directions, then the corresponding secondary phase windings, which are connected in series with each other,— s_1' and s_1'' , s_2' and s_2'' , s_3' and s_3'' respectively,—create a resultant supplementary voltage, 10 which, at every position of the rotating member of the double regulator, has the same phase angle as the corresponding phase cf_1 , cf_2 , cf_3 of the transformer. This resultant supplementary voltage will also pass 15 through zero, and then the halves of the secondary winding of the double regulator may be short-circuited by the switches u_1 , u_2 , u_3 and v_1 , v_2 , v_3 respectively.

I have described one suitable arrangement 20 of the primary windings of the two halves of the double regulator. Other arrangements will readily suggest themselves to those skilled in the art.

With my invention a smooth voltage regulation may be obtained by simple switching operations. Sparking is avoided, since at 25 the switch contacts neither a stationary potential difference exists nor one which is caused by the interruption of current. That 30 is, the sum of the inductive voltages between a and b of each phase caused by the variation of the current distribution in the secondary windings in connecting or disconnecting one of the ends a , b , is always equal 35 to zero.

What I claim as new and desire to secure by Letters Patent of the United States, is,—

1. The combination with a regulating winding provided with taps and a terminal 40 connected to one end of said winding, of an induction regulator, a second terminal connected to approximately the center of the secondary winding of the induction regulator, switching means for connecting the 45 ends of said secondary winding to said taps, and means for short-circuiting each half of the regulator secondary winding.

2. The combination with polyphase regulating windings provided with taps, of a 50 double induction regulator having the secondary windings of each phase connected in series and having the primary windings so connected and related thereto as to produce opposing electromotive forces therein when 55 the secondaries are turned ninety degrees electrically from the maximum buck or boost position, terminals connected to the secondaries, and switching means to connect the ends of the secondaries to the taps.

3. The combination with polyphase regulating windings provided with taps, of a 60 double induction regulator having the secondary windings of each phase connected in series and the primary windings so connected and related thereto as to produce opposing 65 electromotive forces therein when the secondaries are turned ninety degrees electrically from the maximum buck or boost position, terminals connected to the secondaries, and switching means to connect the ends of the secondaries to the taps and to short-circuit the group of secondary windings of each phase.

4. The combination with polyphase regulating windings provided with taps, of a 70 double induction regulator having one secondary winding of each phase divided into two sections and a second secondary winding of the same phase connected in series with and between the sections of the first 75 mentioned secondary winding and having the primary windings so connected and related to the secondary winding as to produce opposing electromotive forces in the different secondaries of each phase when the 80 secondaries are turned ninety degrees electrically from the maximum buck or boost position, terminals connected to the mid points of the second mentioned secondary windings, and switching means to connect 85 the ends of the secondaries to the taps.

5. The combination with polyphase regulating windings provided with taps, of a 90 double induction regulator having one secondary winding of each phase divided into two sections and a second secondary winding of the same phase connected in series with and between the sections of the first 95 mentioned secondary winding and having the primary windings so connected and related to the 100 secondaries as to produce opposing electromotive forces in the different secondaries of each phase when the secondaries are turned ninety degrees electrically from the maximum buck or boost position, mains connected to the mid points of the second 105 secondaries, and switching means to connect the ends of the secondaries to the taps, and to short circuit each group of one-half of each second mentioned secondary winding 110 and the adjacent section of the first mentioned secondary winding.

In witness whereof, I have hereunto set my hand this 10th day of August, 1912.

HERMANN NEHLSEN.
